*Primary Examiner—Doris V. Coles
Attorney, Agent, or Firm—Wolf, Greenfield & Sachs, P.C.***[57] CLAIM**

The ornamental design for a pocket for a shoe, as shown and described.

DESCRIPTION

FIG. 1 is a perspective view of a pocket for a shoe, showing my new design;

FIG. 2 is a front elevational view thereof;

FIG. 3 is a left side elevational view, the right side being a mirror image thereof;

FIG. 4 is a top plan view thereof;

FIG. 5 is a bottom plan view thereof; and,

FIG. 6 is a perspective view thereof in the open position. The broken line showing of a shoe in FIG. 1 is for illustrative purposes only and forms no part of the claimed design.
